US0D1063605S

(12) United States Design Patent (10) Patent No.: US D1,063,605 S
(45) Date of Patent:  Feb. 25, 2025

(54) PACKAGING CONTAINER FOR FOODSTUFF

- (71) Applicant: CJ CHEILJEDANG
CORPORATION, Seoul (KR)
- (72) Inventors: Hyo Eun Lee, Seoul (KR); Bom I
Park, Seoul (KR); Tae Yeon Kim,
Seoul (KR); Ga Young Kim, Seoul
(KR); Jae Kwon Yun, Seoul (KR); Jun
Sik Moon, Seoul (KR)
- (73) Assignee: CJ CHEILJEDANG
CORPORATION, Seoul (KR)

() Term: 15 Years

(21) Appl. No.: 35/518,603

(22) Filed: Oct. 13, 2022

(80) Hague Agreement Data

Int. Filing Date: Oct. 13, 2022
Int. Reg. No.: DM/225696
Int. Reg. Date: Oct. 13, 2022
Int. Reg. Pub. Date: Oct. 13, 2023

(30) Foreign Application Priority Data

Apr. 14, 2022 (KR) 30-2022-0014763
Oct. 11, 2022 (KR) 30-2022-0041301

(51) LOC (15) Cl. 09-03

(57)

CLAIM

The ornamental design for a packaging container for foodstuff as shown and described.

DESCRIPTION

- 1.1 : Perspective
1.2 : Front
1.3 : Back
1.4 : Left
1.5 : Right
1.6 : Top
1.7 : Bottom

1 Claim, 7 Drawing Sheets
